by # UNITED STATES PATENT OFFICE.

EDWARD C. STOVER, OF TRENTON, NEW JERSEY, ASSIGNOR TO THE
TRENTON POTTERIES COMPANY, OF NEW JERSEY.

DESIGN FOR A VENTILATED SANITARY FIXTURE.

SPECIFICATION forming part of Design No. 31,090, dated June 27, 1899.

Application filed June 3, 1899. Serial No. 719,311. Term of patent 14 years.

To all whom it may concern:

Be it known that I, EDWARD C. STOVER, of Trenton, in the State of New Jersey, have invented a certain new Design for Ventilated Sanitary Fixtures, of which the following is a specification, referring to the accompanying illustrations of the design.

In the drawings, Figure 1 is a side view, and Fig. 2 a rear view, of a fixture embodying the new design.

The principal feature in the design is the conformation of the fixture at the portions where the vent-passage leads upward and rearward from the bowl, showing on the side

of the fixture merely an upwardly and rearwardly inclined bulge or rounded surface, as shown at *v*, leading upward and merging into the vent, as at *w*. This gives an external contour to the fixture that combines in appearance simplicity and neatness.

2c

What I claim as new is the following:

The design for a ventilated sanitary fixture, as shown and described.

Signed this 11th day of May, 1899.

EDWARD C. STOVER.
